UNITED STATES PATENT OFFICE.

SOLOMON CAHAN, OF NEW YORK, N. Y.

BEDSPRING FABRIC.

Application filed December 19, 1922. Serial No. 607,839.

To all whom it may concern:

Be it known that I, SOLOMON CAHAN, a citizen of the United States, residing in New York, in the county of New York and 5 State of New York, have invented certain new and useful Improvements in a Bed-spring Fabric, of which the following is a specification.

The present invention relates to spring 10 fabrics, and particularly to spring fabrics used in connection with beds, couches and other articles for reclining or sitting thereon, and one object is to provide a fabric of this character composed of longitudinal 15 links and lateral or spacing links, the links being connected to form the fabric by engagement of hook portions of the links with indented or pocket portions of other links.

Another object is to provide a spring 20 fabric of the character mentioned in which the links are of a form adapted to provide the requisite resiliency, together with increased bearing surfaces of the links for supporting the weight imposed thereupon.

25 Another object is to provide a spring fabric of the character mentioned composed of longitudinal links and lateral or spacing links cooperating therewith to form a fabric which will not lessen materially in width 30 due to the weight imposed thereon.

I accomplish these and such other objects and advantages as may appear during the subjoined description by way of example of one embodiment of the invention 35 shown in the accompanying drawings, in which Figure 1 is a plan view of the spring fabric viewed from the under side thereof and shown broken longitudinally and transversely for convenience of illustration, 40 and indicating that it is composed in width and length of a greater number of links than are shown in said view:

Fig. 2 is a sectional view of the spring 45 fabric on the line 2--2 of Fig. 1;

Fig. 3 is a side elevation of a lateral or spacing link on an enlarged scale;

Fig. 4 is an end elevation of the link 50 shown in Fig. 3; and

Fig. 5 is a detail view of a modified form 55 of end connection.

Similar reference characters denote similar parts throughout the several views.

The spring fabric is shown in connection 60 with a frame having side-pieces 10 and end-pieces 11 and 12, but I do not restrict my

self to a frame of any particular form or construction.

The spring fabric comprises in its main parts or elements, the mid-links 13, the marginal links 14, the lateral or spacing links 60 15, the end-connecting mid-links 16 having yokes, the end-connecting marginal links 17 having yokes, the end-connecting mid-links 18 having eyes, and the end-connecting marginal links 19 having eyes.

65 The mid-links 13 are lengths of suitable wire, the wire being bent at intermediate portions thereof to form yoke ends and parallel arms, the arms being of equal length. The yoke ends have inwardly extending portions 20 and indentations or pockets 21 which pockets are substantially semi-circular in configuration on each side of the extensions 20, the parallel arms terminating in hooks 22 arranged in planes 70 transversely to the planes of the inward extensions 20, the purpose of the inward extensions 20 being to space the indentations or pockets 21 apart and provide greater 75 resiliency for the links and an increased 80 amount of supporting surface of the links for the weight imposed thereon.

85 The marginal links 14 are similar to the mid-links 13 except that the marginal links are provided with parallel arms of unequal 90 length, the shorter arms being the same in length as the parallel arms of the mid-links.

95 The lateral or spacing links 15 are lengths of wire, bent to form yokes of substantially elongated W-shape, having inward extensions 23 with indentations 24 substantially semi-circular in configuration on each side thereof, the ends or arms 25 of the yokes being extended substantially parallel to each other and parallel to the inward extensions 23 for the length of the inward extensions and bent to form hooks 26, which lie in planes transversely to the planes of the inward extensions 23, the purpose of the extensions 23 being to space the indentations or pockets 24 apart and provide greater 100 resiliency for the links and an increased amount of supporting surface of the links for the weight imposed thereon.

105 The end-connecting mid-links 16 and end-connecting marginal links 17 are lengths of wire bent at intermediate portions to form yoke end similar to the yoke ends of the mid-links 13, having inward extensions 27 and indentations or pockets 28 substan- 110

tially semi-circular in configuration on each side thereof. The arms of the end-connecting mid-links 16 and marginal links 17 converge from the yokes and at their converging ends are bent to form hooks 29 which lie in planes transversely to the planes of the yoke ends.

The end-connecting mid-links 18 and end-connecting marginal links 19 are lengths of wire bent at intermediate portions to form eyes 30. The arms of the end-connecting mid-links 18 and marginal links 19 diverge from the eyes 30 and at their diverging ends are bent to form hooks 31 which lie in planes transversely to the planes of the eyes 30.

For connecting the end mid-links 16 and end marginal-links 17 to the end-piece 12, the mid and marginal resilient helix members 32 and 33 and mid and marginal rings 34 and 35 are provided; and for connecting the end mid-links 18 and end marginal-links 19 to the end-piece 11, the mid and marginal resilient helix members 36 and 37 are provided.

25 The spring fabric when in assembled form consists of mid-links 13, marginal-links 14, end-connecting mid-links 16 and 18 and end-connecting marginal-links 17 and 19 arranged in connected relation to each other longitudinally of the frame and resiliently connected to the end-pieces thereof, and a plurality of series of lateral or spacing links 15 arranged transversely of the frame in connected relation to each other and to the mid-links 13, marginal-links 14, end-connecting mid-links 16 and 18 and end-connecting marginal-links 17 and 19.

In assembling the spring fabric mid resilient helix members 32 are connected by hooks at one end thereof to the end-pieces 12, the hooks of these helix members engaging in interior spaced holes 38 arranged in the end-piece, the hooks at the opposite ends of the mid helix members being engaged with the mid rings 34. The marginal helix members 33 are connected by the hooks at one end thereof to the end-piece 12, the hooks of these helix members engaging in the marginal spaced holes 39 of the end-piece, the hooks at the opposite ends of the marginal helix members being engaged with the marginal rings 35. The hooks 29 of the end-connecting mid-links 16 are engaged with the mid rings 34, and the hooks 29 of the end-connecting marginal-links 17 are engaged with the marginal rings 35.

60 In the transverse series of spacing links arranged in the line $x-x$ of Fig. 1, the inner spacing links 15 constitute interior spacing links and the outermost links 15 constitute marginal spacing links. The interior spacing links 15 are connected to the end-connecting mid-links 16 by engagement of the hooks 26 of the spacing links in the pockets 28 of the end-connecting mid-links, the hooks 26

of the outer arms of the marginal spacing links engaging the inner pockets 28 of the end-connecting marginal-links 17. The mid-links 13 are connected to the interior spacing links 15 by engagement of the hooks 22 of the mid-links in the pockets 24 of the interior spacing links. The marginal-links 14 are connected to the marginal spacing links 15 and to the end-connecting marginal-links 17 by engagement of the hooks 22 of the short arms of the marginal-links 14 in the outer pockets 24 of the marginal spacing links 15 and engagement of the hooks of the long arms of the marginal-links 14 in the outer pockets 28 of the end-connecting marginal-links 17.

In the transverse series of spacing links arranged in the line $y-y$ of Fig. 1, the interior spacing links 15 are connected to the mid-links 13 by engagement of the hook ends 26 of the interior spacing links in the pockets 21 of the mid-links, the marginal spacing links being connected to marginal-links 14 by engagement of the outer hooks 26 of the marginal spacing links in the inner pockets 21 of the marginal-links 14. The mid-links 13 next in progression are connected to the interior spacing links 15 by engagement of the hooks 22 of the mid-links 13 in the pockets 24 of the interior spacing links, and the marginal-links 14 next in progression are connected to the marginal spacing links 15 and to the prior connected marginal spacing links 14 by engagement of the hooks 22 of the short arms of the marginal-links 14 in the outer pockets 24 of the marginal spacing links and engagement of the hooks 22 of the long arms of the marginal links 14 in the outer pockets 21 of the prior connected marginal links 14, this arrangement of mid-links, marginal links and transverse spacing links being repeated progressively until the fabric extends longitudinally to the mid-links 13 and marginal links 14 adjacent to the end-connecting mid and marginal links 18 and 19. The last-mentioned mid-links 13 and marginal links 14 are connected at their hook ends to the last prior series of spacing links in the progression, and are connected at their yoke ends to the end-connecting mid and marginal links 18 and 19 by engagement of the hooks 31 thereof in the pockets 21 of the mid-links 13 and marginal links 14.

The end-connecting mid-links 18 are connected to the end-piece 11 by engagement of the hooks at one end of the helix members 36 in the eyes 30 of the end-connecting mid-links and engagement of the hooks at the opposite ends of said members with the spaced holes 38 in the end-piece, the end-connecting marginal-links 19 being connected in a similar manner to the end-piece 11 by the helix members 37 engaging in the spaced holes 39 of the end-piece.

For obviating the use of the rings 34 and 35

35, I provide end-connecting mid-links and end-connecting marginal-links such as 40, shown in Fig. 5, having eyes 41 and hook ends 42 arranged in the same plane, the 5 eyes 41 being engageable with the hooks of helix members 32, and the hooks 42 being engageable with the hooks 22 of marginal links 14, and with the hooks 26 of the spacing links 15.

10 It should be noted that as regards the supporting surfaces formed by the yoke ends of the links, especially by the longitudinal links and the spacing links 15, whether the longitudinal links are marginal links 14 or mid links 13, there is formed a staggered arrangement, as is clearly indicated along the lines at $x-x$ or $y-y$ in Fig. 1.

Having thus described my invention, it should be understood that there may be 20 modifications thereof and variations therein without departing from the spirit of the invention or exceeding the scope of the appended claims.

What I claim and desire to protect by 25 Letters Patent is:

1. In a spring fabric, the combination of longitudinal links having yoke ends with pocket portions and supporting surfaces between the pocket portions and having arms 30 with hooks thereon; and spacing links having pocket portions and supporting surfaces between the pocket portions and having arms with hooks thereon; the hooks of the spacing links engaging pocket portions of the 35 yoke ends of the longitudinal links, and the hooks of the longitudinal links engaging pocket portions of the spacing links for interconnecting the spacing and longitudinal links.

40 2. In a spring fabric, the combination of longitudinal links having yoke ends with pocket portions and supporting surfaces between the pocket portions and having arms with hooks thereon; and spacing links having pocket portions and supporting surfaces 45 between the pocket portions and having arms with hooks thereon, the supporting surfaces of the spacing links extending in the longitudinal line of the arms thereof for substantially the length of the arms; the 50 hooks of the spacing links engaging pocket portions of the yoke ends of the longitudinal links, and the hooks of the longitudinal links engaging pocket portions of the 55 spacing links for interconnecting the spacing and longitudinal links.

3. In a spring fabric, the combination of longitudinal links having yoke ends with pocket portions and supporting surfaces between the pocket portions and having arms 60 with hooks thereon; and spacing links having pocket portions and supporting surfaces between the pocket portions and having arms with hooks thereon; the hooks of the 65 spacing links engaging pocket portions of the

yoke ends of the longitudinal links, and the hooks of the longitudinal links engaging pocket portions of the spacing links for interconnecting the spacing and longitudinal links, the supporting surfaces of the yoke 70 ends of the longitudinal links and the supporting surfaces of the spacing links constituting a series of supporting surfaces extending transversely of the spring fabric.

4. In a spring fabric, the combination of 75 longitudinal links having yoke ends with pocket portions and supporting surfaces between the pocket portions and having arms with hooks thereon; and spacing links having pocket portions and supporting surfaces 80 between the pocket portions and having arms with hooks thereon; the hooks of the spacing links engaging pocket portions of the yoke ends of the longitudinal links, and the hooks of the longitudinal links engaging pocket portions of the 85 spacing links for interconnecting the spacing and longitudinal links, the supporting surfaces of the yoke ends of the longitudinal links and the supporting surfaces of the spacing links constituting a series of supporting surfaces 90 extending transversely of the spring fabric.

5. In a spring fabric, the combination of 95 longitudinal links having yoke ends with pocket portions and supporting surfaces between the pocket portions and having arms with hooks thereon; and spacing links having pocket portions and supporting surfaces 100 between the pocket portions and having arms with hooks thereon, the supporting surfaces of the spacing links extending in the longitudinal line of the arms thereof for substantially the length of the arms; the 105 hooks of the spacing links engaging pocket portions of the yoke ends of the longitudinal links, and the hooks of the longitudinal links engaging pocket portions of the 110 spacing links for interconnecting the spacing and longitudinal links, the supporting surfaces of the yoke ends of the longitudinal links and the supporting surfaces of the spacing links constituting a series of supporting surfaces 115 extending transversely of the spring fabric.

6. In a spring fabric, the combination of 120 longitudinal links having yoke ends with pocket portions and supporting surfaces between the pocket portions and having arms with hooks thereon; and spacing links having pocket portions and supporting surfaces 125 between the pocket portions and having arms with hooks thereon, the supporting surfaces of the spacing links extending in the longitudinal line of the arms thereof for substantially the length of the arms; the hooks of the spacing links engaging pocket portions of the yoke ends of the longitudinal links, and the hooks of the longitudinal links 130 engaging pocket portions of the spacing links.

- 2 ing links for interconnecting the spacing and longitudinal links, the supporting surfaces of the yoke ends of the longitudinal links and the supporting surfaces of the 5 spacing links constituting a series of supporting surfaces arranged in staggered relation to each other extending transversely of the spring fabric.
7. In a spring fabric, the combination of 10 marginal links having yoke ends with pocket portions and supporting surfaces between the pocket portions and having arms of unequal length with hooks thereon; and spacing links having pocket portions and supporting surfaces between the pocket portions and having arms with hooks thereon; one of the hooked arms of a spacing link 15 engaging a pocket portion of a marginal link, and the shorter hooked arm of the marginal link next in longitudinal alinement in the fabric to the first-mentioned marginal link engaging a pocket portion of the spacing link for interconnecting spacing links and marginal links.
8. In a spring fabric, the combination of 20 marginal links having yoke ends with pocket portions and supporting surfaces between the pocket portions and having arms of unequal length with hooks thereon; and spacing links having pocket portions and supporting surfaces between the pocket portions and having arms with hooks thereon, the supporting surfaces of the spacing links 25 extending in the longitudinal line of the arms for substantially the length of the arms; the long hooked arm of a marginal link engaging a pocket portion of a second marginal link, and one hooked arm of a spacing link 30 engaging the other pocket portion of said second marginal link, and the short hooked arm of the first marginal link engaging the other pocket portion of the spacing link for connecting marginal links to each other and connecting the spacing link to the marginal links.
9. In a spring fabric, the combination of 35 marginal links having yoke ends with pocket portions and supporting surfaces between the pocket portions and having arms of equal length with hooks thereon; the supporting surfaces extending in the longitudinal line of the arms for substantially the length of the arms; one of the hooked arms of a spacing link 40 engaging a pocket portion of a marginal link, and the shorter hooked arm of the marginal link next in longitudinal alinement in the fabric to the first-mentioned marginal link engaging in a pocket portion of the spacing link for interconnecting the spacing links and marginal links.
10. In a spring fabric, the combination of 45 marginal links having yoke ends with pocket portions and supporting surfaces between the pocket portions and having arms of unequal length with hooks thereon; and spacing links having pocket portions 50 and supporting surfaces between the pocket portions and having arms with hooks thereon; the long hooked arm of a marginal link

engaging a pocket portion of a second marginal link, and one hooked arm of a spacing link engaging the other pocket portion of 55 said second marginal link, and the short hooked arm of the first marginal link engaging the other pocket portion of the spacing link for connecting marginal links to each other and connecting the spacing link 60 to the marginal links.

11. In a spring fabric, the combination of marginal links having yoke ends with pocket portions and supporting surfaces between the pocket portions and having arms 65 of unequal length with hooks thereon; and spacing links having pocket portions and supporting surfaces between the pocket portions and having arms with hooks thereon, the supporting surfaces of the spacing links 70 extending in the longitudinal line of the arms for substantially the length of the arms; the long hooked arm of a marginal link engaging a pocket portion of a second marginal link, and one hooked arm of a 75 spacing link engaging the other pocket portion of said second marginal link, and the short hooked arm of the first marginal link engaging the other pocket portion of the spacing link for connecting marginal links 80 to each other and connecting the spacing link to the marginal links.

12. In a spring fabric of the character described, links having pocket portions and supporting surfaces between the pocket portions and having parallel arms of equal length with hooks thereon; the supporting surfaces extending in the longitudinal line of the arms for substantially the length of the arms. 85

13. In a spring fabric of the character described, links of substantially W-shape having pocket portions and supporting surfaces between the pocket portions and having arms with hooks thereon; the supporting 90 surfaces extending in the longitudinal line of the arms for substantially the length of the arms; the hooks on the arms being transverse to the plane of the arms and the supporting surfaces. 95
